UNITED STATES PATENT OFFICE.

JOHN DAVIDSON, OF PENDLETON, ENGLAND.

TERMINAL-EXHAUST STEAM-ENGINE.

1,084,404.

Specification of Letters Patent. Patented Jan. 13, 1914.

Application filed May 20, 1911. Serial No. 628,370.

To all whom it may concern:

Be it known that I, JOHN DAVIDSON, a subject of the King of Great Britain, residing at Pendleton, in the county of Lancaster, 5 Kingdom of Great Britain, have invented certain new and useful Improvements in Terminal-Exhaust Steam-Engines, of which the following is a specification, reference being had thereto to the accompanying 10 drawing.

This invention relates to improvements in the cylinders of the class of engines known as central exhaust steam engines in which the steam always flows in one direction, the 15 inlet being controlled by valves while the exhaust takes place, when the piston uncovers ports when near the end of its stroke.

The object of my invention is to provide 20 means for economizing steam without detracting from the efficiency of the engine. For this purpose I jacket the cylinder in the usual way around the barrel and cylinder head as far as practicable, but in order to increase the efficiency of the jacket, I cause 25 the steam to circulate around the barrel and afterward across the cylinder head, or in the reverse direction before entering the cylinder through the admission valve.

In the case of small engines where the 30 admission valves have a thoroughfare through them, I cause one half only of the steam to pass through the jacket. I attain this object by the means illustrated in the accompanying drawings, in which—

Figure 1 is a longitudinal section of a central exhaust cylinder constructed in accordance with one embodiment of my invention, and Fig. 2 a fragmentary longitudinal section of a central exhaust cylinder constructed 35 in accordance with another embodiment.

Similar letters refer to similar parts throughout the several views.

Referring to the drawing *a* are the steam inlets, *b* the steam jackets around the cylinder ends, communicating with the said steam inlets, *c* the steam admission ports leading from the steam admission valve casting *d* to the cylinder, *e* the cylinder heads which have each a chamber *f* and two pas-

sages *g* and *h* leading therefrom, the former 50 to the valve casing *d* and the latter to the jacket *b*.

Referring to Fig. 1, according to one embodiment of my invention and when employing steam admission valves *i* having no 55 thoroughfare the whole of the steam passes from the inlet *a* first into the jacket *b* around the cylinder end, then through the passages *h* and chamber *f* passage *g* in the cylinder head *e* and finally through the admission valve and port *c* into the cylinder or vice-versa, the steam from the inlet *a* passes first through the passage *g*, chamber *f*, passage *h* in the cylinder head, then through the jacket *b* and finally through the admission valve and port *c* into the cylinder. 60

In the drawing the lower valve is shown in its open position and the arrows indicate the path taken by the steam.

Referring to Fig. 2 which illustrates 70 another embodiment of my invention, more particularly applicable to small engines provided with tubular steam admission valves and having a comparatively small area to be heated, only one half of the steam is utilized for heating before entering the cylinder and the other half is allowed to pass directly into the cylinder. For this purpose the passage *h* to the valve is restricted, so that when the steam admission valve *l* is 75 open only one half of the steam will pass from the inlet *a* through the passage *h* and the inner end of the admission valve *l* into the port *c* and the cylinder as indicated in the drawings by an arrow. The other half 80 of the steam is caused to pass from the inlet *a* into the jacket *b* around the cylinder end, then across the passage *h*, chamber *f* and passage *g* in the cylinder head *e* to the outer end of the admission valve *l* and enters the 85 port *c* and the cylinder through the outer end of the admission valve *l* as indicated in the drawings also by an arrow.

I claim:

In a central exhaust steam engine having 90 a live steam admission valve at, and a steam jacket around each end of the cylinder and a steam chamber in each cylinder head, a

steam inlet in proximity to the said valve and in communication with the said steam jacket, a passage connecting the said steam jacket and the said steam chamber together at an approximately diametrically opposite point to the said valve, and a passage connecting the said steam chamber and the said valve together, for the purpose of compelling live steam to circulate through the said

steam jacket and steam chamber before entering the said valve.

In testimony whereof I have affixed my signature in presence of two witnesses.

JOHN DAVIDSON.
